Primary Examiner—Philip S. Hyder*Assistant Examiner*—Richelle Shelton*Attorney, Agent, or Firm*—Renner, Kenner, Greive, Bobak, Taylor & Weber**[57] CLAIM**

The ornamental design for a tire iron, as shown and described.

DESCRIPTION

FIG. 1 is a fragmentary perspective view of a tire iron showing our new design, the tire iron being broken in the center to disclose indeterminate length;

FIG. 2 is a fragmentary top plan view thereof, the tire iron being broken in the center to disclose indeterminate length;

FIG. 3 is a fragmentary side elevational view thereof, the opposite side elevational view being substantially the same, the tire iron being broken in the center to disclose indeterminate length;

FIG. 4 is a fragmentary bottom elevational view thereof, the tire iron being broken in the center to disclose indeterminate length;

FIG. 5 is a front elevational view thereof;

FIG. 6 is a rear elevation view thereof; and,

FIG. 7 is a top plan view of an alternative embodiment of a tire iron wherein the perspective view, side elevational view, bottom elevational view, front elevational view and rear elevational view of the embodiment are substantially the same as shown in FIGS. 1, 3, 4, 5 and 6, respectively.
